(57) **CLAIM**

The ornamental design for a controller for medical equipment as shown and described.

DESCRIPTION

FIG. 1 is a front, top and right side perspective view of a controller for medical equipment according to the design; FIG. 2 is a rear, top and left side perspective view thereof; FIG. 3 is a front, bottom and right side perspective view thereof;

FIG. 4 is a front view thereof;

FIG. 5 is a left side view thereof;

FIG. 6 is a right side view thereof;

FIG. 7 is a top plan view thereof;

FIG. 8 is a bottom plan view thereof;

FIG. 9 is a rear view thereof;

FIG. 10 is a cross-sectional view taken along line 10-10 of FIG. 4; and,

FIG. 11 is a cross-sectional view taken along line 11-11 of FIG. 4.

The broken lines illustrate portions of the controller for medical equipment that form no part of the claimed design.

1 Claim, 5 Drawing Sheets
